ARTICLE TRANSFERRING MECHANISM

Clare S. Riley, Windsor, Conn., assignor to Hartford-Empire Company, Hartford, Conn., a corporation of Delaware

Application June 5, 1935, Serial No. 25,015

16 Claims. (Cl. 294—88)

This invention relates to article transferring mechanism and more particularly to a tongs mechanism usable in stacking articles, such as bottles, in close relation to each other.

5 In the use of stacking devices of the type which pick up an article, such as a bottle, from a conveyor or buck at a predetermined point and set it down at a delivery station, which may be on the conveyor belt of a glassware annealing lehr, some difficulty has arisen when the articles are being stacked close together, due to the fact that the full opening of the tongs in releasing an article has caused the tongs to impinge against adjacent articles and sometimes knock them over. This difficulty is more pronounced when the articles being handled are relatively small as compared to the size of the tongs and/or where they are placed close together on the receiving surface, as on a lehr conveyor.

20 The primary object of my present invention therefore is to provide means for overcoming the difficulty above set forth, specifically by providing a means for limiting the opening movement of tongs in releasing an article at the delivery station or position, while permitting the full opening of the tongs at some subsequent time, preferably after the tongs and their carrier or support have been moved bodily away from the delivery position, so that the full opening of the 25 tongs will not cause them to hit adjacent articles. It is desired that tongs used in stacking glassware, and for certain other purposes, be fully opened prior to their being brought to the receiving station in order that they may grasp 30 articles which may not be accurately spotted at that station.

A further and relatively specific object of my present invention is to provide for the adjustment of the degree of the initial or partial opening of the tongs in a manner independent of the 40 fully opened or fully closed positions, so as to compensate for the different spacing between articles usable, for example, when the device is used on a lehr stacker.

45 A further specific object of the invention is to provide adjustable timing means for controlling as desired the interval between the initial or partial opening of the tongs and the subsequent or full opening thereof.

50 Other and more specific objects of the present invention will appear from the following description of a preferred embodiment thereof and in the appended claims, all when taken in conjunction with the accompanying drawings in 55 which:

Figure 1 is a view principally in elevation of stacker tongs with my improved device associated therewith, certain of the operating means for the tongs opening retarding mechanism being shown in vertical section; 5

Fig. 2 is a view of the device principally in central vertical section taken at right angles to the view of Figure 1;

Fig. 3 is a view partly in plan and partly in horizontal section of the device, the sectional view being on the line 3—3 of Figs. 1 and 2;

Fig. 4 is a view substantially in horizontal section on the line 4—4 of Fig. 2;

Fig. 5 is a fragmentary view similar to Fig. 1 but at a different angle and showing certain of 15 the passage means between the main tongs operating mechanism and the auxiliary cylinder, the parts in section being shown on the line 5—5 of Fig. 3;

Fig. 6 is a fragmentary view in elevation showing an application of mechanism embodying my 20 invention; and

Fig. 7 is a fragmentary view in horizontal section taken on the line 7—7 of Fig. 5.

I have chosen to illustrate my invention as 25 applied to the stacking tongs of the "Hartford-Empire stacker", which is shown in Lorenz Patent No. 1,878,156, granted September 20, 1932. Fig. 6 of the present drawings corresponds generally to the lower portion of Fig. 3 of the Lorenz 30 patent. It will be understood, however, that my invention may be applied not only in other types of stackers, but also in devices usable for some-what different purposes, and in fact wherever the 35 results attainable by the use of the invention are applicable.

In its normal operation, the "Hartford-Empire stacker" is arranged to pick up bottles or other glass articles at a single position on a buck or conveyor and place these bottles in different positions on the conveyor belt of a glass annealing lehr. The result of stacking as attained by the "Hartford stacker" is that the entire or a predetermined part of the area of the lehr conveyor is filled with the articles which are being stacked 45 in substantially uniformly spaced relation, the articles being preferably close together, but not touching.

It will be understood therefore, that while the 50 present claims refer to a "receiving position", which is in the usual case a single position at which the articles are spotted on the conveyor or buck to be picked up, and also refer to a "delivery position", this last position may be and in fact 55 is a plurality of different positions on the con-

- veyor belt of the lehr in the case of the "Hartford-Empire stacker". This variation in the actual point at which bottles are delivered by the stacker is accomplished by a lateral indexing 5 movement of the stacker mechanism about a center which is in vertical alignment with the receiving position for the bottles. However, inasmuch as this feature is not a part of my present invention, but is disclosed and claimed in the 10 Lorenz patent above referred to, it is not thought necessary to go into detail except to bring out that the "delivery position" expressed in the appended claims may not be one single position, but is to be construed as including any and all points 15 at which bottles or other articles being transferred are delivered by the stacking or transferring means provided.
- Referring first to Fig. 6, which as above stated corresponds generally to a part of Fig. 3 of the 20 Lorenz patent above referred to, there is illustrated a depending bracket 1, which is supported from above in a manner specifically described in the Lorenz patent. To the lower end of the bracket 1, there is pivoted at 2 a swinging arm 3 on which the stacker tongs hereinafter to be described are suitably mounted. For swinging the arm 3 about the axis 2, there is provided a sprocket chain 4 engaging with a sprocket wheel 5 which is secured to the arm 3. One end of the sprocket 25 chain 4 is connected to a resilient device 6 while the other end is connected to a suitable crank both shown and described in detail in the Lorenz patent, but not illustrated in the accompanying drawings. Sufficient be it to say for the present 30 purposes that movement is imparted to the sprocket wheel 5 and the arm 3 through the sprocket chain 4 from suitable operating mechanism to move the arm between the full and dotted line positions shown in Fig. 6. A spring 7 is 35 connected between a suitable anchorage and a bracket 8 rigid with the arm 3 to serve as a counterbalance and for certain other purposes, all of which are fully described in the Lorenz patent.
- 40 The outer end of the arm 3 supports a suitable pintle on which is secured a split bracket 9 which clamps around the barrel portion 10 of the tongs support which is generally indicated at 11. In order that the tongs may be retained vertical to sustain an article in vertical position during the movement thereof from the buck B to the lehr conveyor L shown in Fig. 6, there is provided a parallel motion device comprising a sprocket wheel 12 which is secured to a sleeve 45 rigid with the bracket 1 and also a sprocket 13 having the same number of teeth and pitch as the sprocket 12 and which is secured to the pintle carrying the split bracket 9. Surrounding the 50 sprocket wheels 12 and 13 is a sprocket chain 14, the ends of which may be connected by a spiral tension spring 15 as shown. The sprocket 12 being secured to the bracket 1 does not rotate and hence rotation of the arm 3 around the axis 2 will cause the chain 14 to move about the 55 sprockets 12 and 13 without any variation of the sprocket 13 from its initial angular position in respect to the vertical, thus retaining the barrel portion 10 of the tongs support 11 always vertical.
- 60 In this way articles such as the bottle A are picked up at the receiving position shown at the right in Fig. 6 and moved to the position at which the bottle C is located on the belt L, the tongs being shown at this position just releasing the 65 article and being partly opened so as not to en-

gage and topple over the bottle D adjacent to the bottle C. The means for opening the tongs only partially in releasing a bottle form the principle subject matter of the present invention as hereinafter to be described.

The barrel portion 10 of the tongs support 11 is clamped in a desired vertically adjusted position by suitable bolts 16 in the split bracket 9. At the lower end of the support 11 there is secured a fluid pressure cylinder 17. This cylinder 10 is formed with a reduced portion 18 (Fig. 2), which is secured within the lower end of the barrel 10 and which is formed with an axial bore 19 extending vertically therethrough. A piston 20 is mounted for vertical reciprocation within the cylinder 17 and is provided with a piston rod 21 which extends through the bore 19 and upwardly through the barrel 10. The piston 20 is urged upwardly by a coil spring 22 which encircles the rod 21 and which is interposed between a sleeve 23 loosely surrounding the lower end of the rod 21 adjacent to the reduced portion 18 of the cylinder 17 and an adjustable nut (not shown) which is threaded onto the upper end of the rod 21. This nut may be so positioned as to engage 25 beneath an adjustable stop screw 24 (Fig. 6) for limiting the closing movement of the tongs by limiting the upward movement of the piston 20 in cylinder 17.

The lower edge of the cylinder 17 is provided 30 with diametrically opposed pairs of depending ears 25 (Fig. 1), between each pair of which a tongs holder 26 is pivotally mounted by means of a pivot pin 27. The tongs comprise a pair of gripping fingers 28, one of which is detachably 35 secured to each of the holders 26 and each of which is formed with an inwardly projecting portion 29 provided with a suitable notch or groove for engaging beneath the neck finish 30 of a bottle, as shown in Fig. 2. The tongs holders 26 are also each provided with an inwardly 40 projecting arm 31 which are offset relative to each other (Fig. 4) and which are each pivotally connected to the lower end of one of a pair of links 32 (Figs. 2 and 4). The upper ends of the 45 links 32 are pivotally connected to the piston 20 by means of a wrist pin 33 and are maintained in spaced relation to each other by means of a spacing washer 34. By means of this construction, when air pressure is admitted to the cylinder 17, the piston 20 will be depressed, thus causing the gripping fingers 28 of the tongs to open, whereas when air pressure within the cylinder is relieved, the spring 22 will elevate the piston 20 and close the tongs about the ware. It will be 55 apparent that the ware is yieldingly engaged by the tongs by a predetermined spring pressure which is in practice adjustable. As has been pointed out before, the limit of the closing movement of the tongs may be accurately adjusted according to the diameter of the neck of the ware by means of the adjusting screw 24. This closed 60 position of the tongs may also be adjusted by means of threaded bolts 35 which serve not only to secure the tongs 28 to the holders 26, but also 65 are elongated and extend inward so that they may be adjusted to abut each other at the closed position of the tongs. These screws are threaded in the tongs members 26 so that they may be 70 adjusted in and out to predetermine the closed position of the tongs as aforesaid and are provided with nuts 36 for clamping the tongs members 28 to their holders 26. Either or both of the above-named adjustments may be employed 75 to predetermine the closed position of the tongs. 75

Pressure may be conducted from a suitable valve means under control of a timer (not shown) to the cylinder 17, this pressure being transmitted to the cylinder in the same way as is specifically disclosed in the Lorenz patent above referred to. Briefly, pressure is conducted, in a manner not particularly illustrated here, down the bracket 4 (Fig. 6) and thence through suitable transmitting means, some of which are preferably concentric with the axis 2 of the arm 3, thence through a hollow portion of the arm 3 and suitable pressure transmitting passages in the pintle on which the split bracket 9 is mounted to a chamber inside the bracket, whence the pressure may pass through a hole 37 (Fig. 2) in the barrel portion 10 of the tongs support to the interior of this barrel portion. Pressure may then pass between the piston rod 21 and the loose sleeve 23 and through a groove 38 cut in the piston rod past the bore 19 of the reduced portion 18 of the cylinder 17 and into the upper end of the cylinder. Suitable means may be provided as disclosed specifically in the Lorenz patent above referred to for controlling the application and exhaust of pressure at the desired times. The construction thus far described is substantially identical with that disclosed in the Lorenz patent, and while it has been briefly treated herein, reference may be had to the Lorenz patent for a specific description of the various mechanisms of the stacker.

I have shown at 39 (Fig. 2), a plug in the upper portion of the cylinder 17 which may be utilized in practice for plugging a hole at which point a pressure gage may be screwed in if desired. This is merely an operating device convenient in testing the apparatus and is shown herein, as the present drawings were made from the working drawings of the commercial device.

I have also illustrated in Fig. 2 a vent passage 40 controlled by an adjustable bleed valve 41 which may be used in practice to insure the rapid exhaustion of pressure from within the cylinder 17, so as to permit the rapid closing of the tongs. The valve 41 is adjusted, however, so that when pressure is supplied to the cylinder 17 for opening the tongs, this pressure will not leak out fast enough to prevent the rapid opening of the tongs.

Means are provided according to my invention for limiting the initial opening movement of the tongs in depositing an article to a point just sufficient for releasing the article, while preventing the full opening thereof for a predetermined and preferably adjustable time during which the tongs may be moved bodily away from the delivery position and such that the full opening thereof will not cause them to hit an adjacent article.

For this purpose there is provided a second pneumatic cylinder 42 adjacent to the cylinder 17 and preferably secured to the tongs support 11 by being provided with a split clamping member 43 which may be integral therewith and which is secured to the barrel 10 by means of a clamping bolt 44. The cylinder 42 is provided with a piston 45 which is urged to its lowermost position by a compression spring 46 extending between the upper side of the piston and the head of the cylinder. The piston 45 has secured thereto a piston rod 47 which extends vertically downward parallel to the piston rod 21. At the lowermost position of the piston 45 in cylinder 42, the lower end of the piston rod 47 is in alignment with the path of a dog 48 which is arranged for movement with one of the tongs

members 28, the left hand one as seen in Fig. 2.

The dog 48 is loosely mounted on one of the pintles 27, as best shown in Figs. 1, 2 and 4, and is provided with a tail portion 49 having threaded therethrough an adjustable bolt 50, the inner end 5 of which is adapted to engage against an extension 51 of the tongs holder 26 adjacent thereto. A light spring 52 is provided which continuously urges the end of the screw 50 against the extension 51 and thus tends to retain the dog 48 10 in a predetermined relative position in respect to the associated tong 28.

As best shown in Fig. 2, when the tongs are moved from their closed position shown in full lines toward their open position, the dog 48 will 15 be moved in a clockwise direction about the axis of the pinte 27 on which it is mounted, due to the engagement of the inner end of the screw 50 with the extension 51. If at this time the piston rod 47 is in its lowermost position to which it is 20 urged by the spring 46, then the tongs can open a predetermined amount only, specifically to the dotted line position shown in Fig. 2, as at that position the upper end of the dog 48 will engage against the lower end of the piston rod 47. The 25 tongs cannot open further until the piston 45 has been raised in cylinder 42, which is accomplished in a manner hereinafter to be described, at which time the tongs may be fully opened under the continued action of pressure in cylinder 17. 30

It will be seen also that the intermediate position of the tongs may be manually adjusted as desired by adjusting the position of the screw 50 in respect to the tail 49 of the dog 48, this adjustment being secured by a jam nut 53.

For moving the piston 45 upwardly in the cylinder 42 when desired for permitting the full opening of the tongs, there are provided pressure passages shown in Figs. 5 and 7 between the 40 interior of the barrel member 10 and the lower end of the cylinder 42. These passages include a pair of aligned transverse bores 54 (Fig. 5), a vertical bore 55 and a system of passages shown in Fig. 7 at 56. Flow of air through the passage-ways 54, 55 and 56 is adjustably controlled by a needle valve 57 (Fig. 7) which may be set at a desired adjusted position and the adjustment secured by a jam nut 58. Thus when pressure is supplied to the cylinder 17 for opening the tongs, 50 the same pressure passes through the passage-ways 54, 55 and 56 to the lower end of cylinder 42 tending to move the piston 45 upwardly against the spring 46 and permit the full opening thereof. However, this pressure to cylinder 42 may only 55 pass into the cylinder slowly under the control of the needle valve 57.

There is further provided in cylinder 42 an enlarged chamber as shown at 59, beneath the piston 45, so that pressure will be some predetermined time in building up sufficiently in the cylinder 42 before the piston 45 is moved upwardly against the spring 46. This in practice affords sufficient time for the tongs to be moved partly open, the article to be released and the tongs to be then moved bodily away from the delivery position. After this time period has elapsed, pressure builds up in cylinder 42, the piston 45 is raised, raising the piston rod 47 and the tongs may then be opened to their fullest 70 open position under the continued action of pressure supplied to the upper end of cylinder 17. This will occur when the piston rod 47 is moved upward sufficiently so that the dog 48 may continue its movement.

The time of release of the dog 48 from the piston rod 47 is preferably manually adjustable by adjusting the needle valve 57, so that the apparatus may be suitably adjusted for different rates of operation.

As above stated, I contemplate that my invention may be applied to any use for which it is applicable or desirable. I further contemplate that any desired means, pneumatic or otherwise, 10 may be employed for retarding the full opening of the tongs for a predetermined and preferably adjustable time after the tongs have been opened partially to release an article for the purpose above set forth or for any other desired purpose.

I contemplate that various changes may be made in the construction and relationship of parts, and equivalent mechanism may be substituted wherever it may be desirable. I do not wish to be limited, therefore, except by the scope of the 20 appended claims, which are to be construed as broadly as the state of the prior art permits.

I claim:

1. Article transferring mechanism, comprising a support, tongs on said support arranged to be 25 opened and closed and to grasp articles to be transferred at a receiving position and deposit the articles after movement of said support at a delivery position, means for closing said tongs to grasp an article at the receiving position, and 30 means for imparting to said tongs a predetermined part only of their opening movement to release an article at the delivery position and thereafter for completing the opening movement of said tongs.

2. Article transferring mechanism, comprising a support, tongs on said support arranged to be 40 opened and closed and to grasp articles to be transferred at a receiving position and deposit the articles after movement of said support at a delivery position, means operative at the receiving position for moving said tongs from their fully opened to their fully closed position in grasping an article to be transferred, and means operative when the tongs have moved an article 45 to the delivery position for moving the tongs from their fully closed position a predetermined distance only toward their fully open position to release an article and after the tongs have been bodily moved by movement of said support away 50 from the delivery position to move the tongs in respect to said support the remainder of the way to their fully open position.

3. Article transferring mechanism, comprising a support, tongs on said support arranged to be 55 opened and closed and to grasp articles to be transferred at a receiving position and deposit the articles after movement of said support at a delivery position, pneumatic means for operating said tongs at least as to the opening thereof, and 60 means for automatically controlling the operation of said pneumatic means in opening said tongs and so constructed and arranged that the tongs can be opened a predetermined part of the way only in releasing an article at the delivery position and thereafter the tongs will be opened to their fullest extent.

4. Article transferring mechanism, comprising a support, tongs on said support arranged to be 65 opened and closed and to grasp articles to be transferred at a receiving position and deposit the articles after movement of said support at a delivery position, pneumatic means for opening said tongs, and other pneumatically operated means for automatically limiting the opening of said 70 tongs at an intermediate position thereof in re-

leasing an article at the delivery position and thereafter to move in such manner and direction as to permit the full opening of the tongs by the first named pneumatic means.

5. Article transferring mechanism, comprising a support, tongs on said support arranged to be 5 opened and closed and to grasp articles to be transferred at a receiving position and deposit the articles after movement of said support at a delivery position, pneumatic means for operating said tongs at least as to the opening thereof, and a pneumatically operated delay action device co-operating with the tongs opening means for limiting the opening movement of the tongs to a predetermined extent in releasing an article held therein and thereafter moving to a position permitting the first-named pneumatic means to open the tongs fully, both said pneumatic means being operated by a single application of pneumatic pressure.

6. Article transferring mechanism, comprising a support, tongs on said support arranged to open and close and to grasp articles to be transferred at a receiving position and deposit the articles after movement of said support at a delivery position, pneumatic means for operating said tongs at least to the opening thereof, and a pneumatic cylinder cooperating with the tongs to delay the full opening thereof for a predetermined time after pressure has been supplied to the first named pneumatic means tending to open the tongs, the parts being so constructed and arranged that the initial application of pressure to the pneumatic means will open the tongs to a predetermined extent only but sufficient to release an article held thereby, and said pneumatic cylinder will thereafter operate to permit the full opening of the tongs.

7. Article transferring mechanism, comprising a support, tongs on said support arranged to be 40 opened and closed and to grasp articles to be transferred at a receiving position and deposit the articles after movement of said support at a delivery position, pneumatic means for operating said tongs at least as to the opening thereof, 45 means for delaying the action of the tongs opening means at an intermediate position of the tongs to the end that an article will be released by the tongs in moving from their closed to their intermediate position and thereafter the tongs may 50 be fully opened, and means for adjustably varying the time interval between the movement of the tongs to their intermediate position and the full-opening thereof.

8. Article transferring mechanism, comprising a support, tongs on said support arranged to open and close and to grasp articles to be transferred at a receiving position and deposit the articles after movement of said support at a delivery position, pneumatic means for operating 60 said tongs at least as to the opening thereof and actuated by the supplying of pneumatic pressure thereto to open the tongs, a pneumatic cylinder having a piston therein cooperating with said tongs for delaying the full opening thereof for a predetermined time after pressure has been supplied to the first-named pneumatic means to open the tongs, and a bleed valve interposed between the first-named pneumatic means and said pneumatic cylinder gradually to admit pressure 65 from the first-named pneumatic means to said pneumatic cylinder for moving the piston thereof in respect to the cylinder after pressure has built up in said pneumatic cylinder and thereby to permit the full opening of the tongs at a predeter- 70 75

mined time subsequent to the partial opening thereof in response to the initial application of pressure to said pneumatic means, whereby the partial opening of the tongs may be utilized to release an article supported thereby and the full opening of the tongs may be delayed by the aforesaid means until the tongs have been bodily moved by movement of said support away from the delivery position so that full opening of the tongs will 5 not cause them to impinge articles adjacent to the one being deposited.

9. Article transferring means, comprising a support, tongs on said support arranged to be opened and closed and to grasp articles to be transferred at a receiving position and deposit the articles after movement of said support at a delivery position, an air cylinder connected with said tongs, spring means associated with said air cylinder and tending at all times to close said tongs, the 10 air cylinder being so constructed and arranged that when pressure is supplied thereto, the tongs will be opened in opposition to said spring means, a second air cylinder having a piston therein associated with said tongs and arranged in one position of the piston thereof to prevent the full opening 15 of said tongs while permitting the partial opening thereof, spring means in said second cylinder tending to move the piston thereof to a position to prevent the full opening of said tongs, a bleed passage between said two cylinders, and a 20 manually adjustable bleed valve in said bleed passage, the parts being so constructed and arranged that in depositing an article at the delivery position of the tongs, pressure is supplied to the first named cylinder tending to open the tongs, this opening movement being limited by the relative position of the second air cylinder and the 25 piston thereof to an intermediate position at which an article is released from the tongs and the piston and second cylinder will thereafter be 30 relatively moved by pressure from the first air cylinder through said bleed valve to permit the subsequent full opening of the tongs under the continued action of the pressure in the first- 35 named cylinder.

40 10. Article transferring mechanism, comprising a support, tongs movably mounted on said support, actuating means for opening and closing said tongs, a dog movably mounted on said support arranged to be moved in a predetermined path by movement of the said tongs, an interrupting device movable into and out of a 45 position in the path of movement of said dog and adapted to interrupt the opening movement of said tongs at an intermediate position thereof when said interrupting device is in one position 50 and after movement of said interrupting device to another position, to permit the full opening of said tongs, and means for moving said interrupting device into and out of its position in the 55 path of movement of said dog.

60 11. Article transferring mechanism, comprising a support, tongs movably mounted on said support and arranged to grasp an article and hold it in a position such that the longitudinal axis of the article will be aligned with the longitudinal axis of said support, a pneumatic cylinder in said support for opening and closing said tongs, a dog movable with one of said tongs, a longitudinally movable rod mounted on said support for movement into and out of position in alignment with the path of movement of said dog, and means for moving said rod, the parts being 65 so constructed and arranged that when 70 said rod is in its position in the path of move- 75

ment of said dog and pressure is supplied to said pneumatic cylinder for opening said tongs, the tongs may be opened a predetermined part of the way only from their fully closed toward their fully opened position but sufficient to release an 5 article previously held therein, and upon movement of said rod, said tongs may be moved to their fully opened position by said pneumatic cylinder.

12. Article transferring mechanism, comprising a support, tongs on said support arranged to be opened and closed and to grasp articles to be transferred at a receiving position and deposit the articles after movement of said support at a delivery position, means for closing said tongs 10 to grasp an article at the receiving position, means for imparting to said tongs a predetermined part only of their opening movement to release an article at the delivery position and thereafter for completing the opening movement 15 of said tongs, and means for adjustably varying the amount of opening movement imparted to said tongs to release an article at the delivery position independently of the time of the partial or full opening of the tongs and of the fully 20 opened or fully closed positions of the tongs.

25 13. Article transferring mechanism, comprising a support, tongs on said support arranged to be opened and closed and to grasp articles to be transferred at a receiving position and deposit 30 the articles after movement of said support at a delivery position, pneumatic means for operating said tongs at least as to the opening thereof, means for automatically controlling the operation 35 of said pneumatic means in opening said tongs and so constructed and arranged that the tongs can be opened a predetermined part of the way only in releasing an article at the delivery position, and thereafter the tongs will be opened to their fullest extent, and means for manually 40 adjusting the intermediate position to which the tongs are opened in releasing an article independent of the fully open or fully closed positions of said tongs.

45 14. Article transferring mechanism, comprising a support, tongs pivotally mounted on said support on parallel axes, a pneumatic cylinder in said support arranged to open and close said tongs, the opening movement of said tongs being in response to the supplying of pressure to one 50 end of said cylinder, a dog mounted for movement with one of said tongs and movable therewith through a predetermined path, a second pneumatic cylinder mounted on said support, the piston rod of which is located in one position of the piston in said second cylinder in the path of movement of said dog, a bleed passage between said cylinders, and means for resiliently urging the piston in said second cylinder to a 55 position at which said piston rod is in the path of said dog, the aforesaid parts being so constructed and arranged that the supplying of pressure to the first named cylinder for opening said tongs will move the tongs to an intermediate position at which said dog will engage the 60 piston rod of the second named cylinder, and subsequently pressure from the first named cylinder passing through said bleed passage will move the piston in said second named cylinder to move its piston rod out of the path of said dog and thus permit the full opening of said tongs.

65 15. Transferring mechanism, comprising a support which is normally maintained vertical during article transfer, a pair of tongs members 70 75

mounted on parallel horizontal axes on said support, a pneumatic cylinder in said support connected to operate said tongs members, spring means for moving the piston in said cylinder to close said tongs, means for adjustably limiting the closing movement of said tongs, a dog mounted axially with one of said tongs but movable in respect thereto, means for adjustably controlling the angular position of said dog with respect to its associated tong, means for resiliently holding said dog in a predetermined position in respect to its associated tong, said position being subject to the angular adjustment therebetween, a second pneumatic cylinder associated with said support having a piston and piston rod and so located that the piston rod thereof will be in alignment with the path of movement of said dog when the piston is at one position, spring means for moving the piston in said second cylinder to the position such that the associated piston rod will be in the path of movement of said dog, and a manually adjustable needle valve controlling passage of pressure between the first and second named pneumatic cylinders, the aforesaid parts being so constructed and arranged that said tongs may be moved at the receiving position for articles from their fully opened to their fully closed positions by the exhausting of pressure from the first named pneumatic cylinder and under the action of the associated spring means, and when said tongs are at their delivery position and it is desired to

release an article, pressure may be supplied to the first named pneumatic cylinder which will move said tongs from their fully closed to an intermediate position at which the article will be released while further opening movement of said tongs at this time is prevented due to said dog engaging the piston rod of the second named pneumatic cylinder, thereby preventing upsetting of the adjacent articles at the delivery position, and subsequently pressure passing from the first to the second named pneumatic cylinders through said needle valve will move said piston rod out of alignment with the path of said dog to permit the full opening of said tongs.

16. Article transferring mechanism, comprising a support, tongs on said support arranged to be opened and closed to grasp articles to be transferred at a receiving position and deposit the articles after movement of said support at a delivery position, means to close said tongs at the receiving position to grasp articles and to open said tongs at the delivery position for releasing articles transferred by the tongs, means effective at the receiving position for temporarily mechanically limiting the opening of the tongs by the aforesaid means, and means for thereafter causing movement of the last-named means to an inoperative position to permit the complete opening of the tongs by the opening means thereof.

CLARE S. RILEY.

30
